UNITED STATES PATENT OFFICE.

MYRON H. TITUS, OF SEATTLE, WASHINGTON.

CIRCULAR-SAW SIDE DRESS.

Application filed December 12, 1925. Serial No. 75,041.

The invention is a device for side dressing shingle or other, circular saws.

The object of the invention is to provide a readily adjustable file holding device that 5 may be held against the side of a circular saw to dress the sides of the teeth.

Another object of the invention is to provide an adjustable side dress for circular saws which is of a simple and economical 10 construction.

A further object of the invention is to provide a side dress for circular saws or the like which may readily be adjusted to saws of different diameters.

15 And a still further object of the invention is to provide a side dress for circular saws or the like in which a file may readily be clamped and in which the angle of the file may readily be adjusted to the angle of 20 the teeth.

With these ends in view the invention embodies a holding frame, a wedge shaped member slidable in said frame, a file holding member adjustably held to the outer end of 25 the said wedge shaped member, and suitable set screws for adjusting the position of the said device.

Other features and advantages of the invention will be seen from the following description taken in connection with the drawings, wherein:—

Figure 1 is a side view of the device with parts broken away.

Figure 2 is a rear view of the upper end 35 of the device.

Figure 3 is a vertical section through the center of the upper end of the device.

Figure 4 is a cross section on line 4—4 of Figure 2.

40 In the drawings I have shown my device as it would be made wherein numeral 1 indicates a holding frame, numeral 2 the wedge shaped member, and numeral 3 the file holding member.

45 The holding frame 1 is made with a flat plate 4 at the lower end and lugs 5 with dovetailed grooves 6 in them extending upward from the edges of the upper part of the plate 4, and in the upper part of the center of the plate 4 is a slot 7 through which a bolt 8 passes to hold the member 2.

50 It will be observed that the bolt 8 is rigidly held in the member 2 and is provided with a nut 9 and a friction washer 10 at its outer end by 55 which it may readily clamp the member 2 in any position along the frame 1. It will

be observed that when the nut 9 is loose the member 2 is free to slide upward or downward in the grooves 6 of the member 1, and with the lower end of the plate 4 placed 60 upon the hub or spindle of the saw, or any suitable object adjacent the center or base, the member 2 may be adjusted to such a position that a file held in the member 3, hereinafter described, will engage the sides of 65 the teeth of the saw, and then the nut 9 may be tightened to rigidly hold the file in place. The member 2 is made as shown, with projections 11 at the sides to engage the grooves 6, and at the upper end is an inclined plate 70 12 having hubs 13 adjacent the lower end, a set screw 14 in the outer end, and openings 15 through which studs 16 from the member 3 may project. Below the plate 12 are projections 17 which extend outward from each 75 side and in which are set screws 18 that are held by lock nuts 19 to hold the set screws in any suitable position. It will be observed that the set screws may be screwed outward until they engage the face of the 80 saw and then locked in position so that they will rigidly hold the file a predetermined distance from the saw.

The member 3 is held in the hubs 13 by set screws 20, and the upper portion of the 85 member 3 is formed with a flat plate having a lug 21 in its upper end in which a set screw 22 is screwed. On the plate 3 is another plate with grooves in the edges that slide over the edges of the plate 3 and a projection 23 at the upper end in which the screw 22 is held. It will be observed that the position of the upper plate may readily be adjusted by the set screw 22, and when a file as indicated by the numeral 24 is 95 placed in the device it will engage a shoulder 25 on the plate 3 and by screwing the set screw 22 inward the file may be rigidly clamped between the shoulder 25 and the lower edge of the upper plate.

100 It will be understood that changes may be made in the construction without departing from the spirit of the invention, one of which changes may be in the design of the holding frame; another may be in the use of 105 other means for holding the member 2 to the holding frame; and still another may be in the use of other means for holding and adjusting the member 2 from the member 3.

110 The construction will be readily understood from the foregoing description. To use the device a file may be placed in the

member 3 as hereinbefore described and it will be observed that by gripping the holding frame 1 and placing the lower end thereof upon an object adjacent the center of the saw the file may readily be held against the side of the teeth to dress the teeth. It will also be observed that the device may be adjusted to saws of different diameters and to teeth of different angles, and a similar device which may be set to a different angle may be used on the opposite side of the saw in a similar manner.

Having thus fully described the invention, what I claim as new and desire to secure by Letters Patent, is:—

In a device of the class described, a

grooved bar, a member slideable in the said grooves, means for holding the member in different positions, another member adjustably held to the outer end of the said latter member, means for holding a file or the like in the said adjustable member, means for readily adjusting the angle of the said adjustable member in relation to the said slideable member, means for locking said angular adjusting means and adjustable means for holding the said device away from the face of an object against which it may be placed.

In testimony whereof I hereby affix my signature.

MYRON H. TITUS.
